UNITED STATES PATENT OFFICE.

GEORGE H. BEST, OF HAMPTON, NEW BRUNSWICK, CANADA.

SET-RING.

No. 857,862.

Specification of Letters Patent.

Patented June 25, 1907.

Application filed October 10, 1906. Serial No. 338,331.

To all whom it may concern:

Be it known that I, GEORGE H. BEST, a subject of Great Britain, residing at Hampton, in the county of Kings and Province of 5 New Brunswick, Canada, have invented new and useful Improvements in Set-Rings, of which the following is a specification.

This invention relates to improvements in set-rings or collars, and the objects of the 10 improvements are to provide for the placing of a set-ring upon any shaft, for the purpose of taking up end play, or for any other purpose, without removing the shaft or either end of it from its bearings.

15 A further object is to provide a set-ring which may be firmly affixed to a shaft without the use of set-screws or bolts or similar appliances, the ring when attached having a rim entirely free from projecting set-screw 20 heads or other projections, thus avoiding the danger to workmen consequent upon the liability of their clothing to catch upon or become entangled by such projections.

25 These objects are obtained by the mechanism illustrated in the accompanying drawings, in which

Figure 1 is an internal side view of one-half or part of one of the sections of the set-ring. Fig. 2 is an external side view of the 30 other half of said section. Fig. 3 is a perspective view of both halves or parts assembled. Fig. 4 is a vertical section thereof. Fig. 5 is an external side view of one-half or part of the other section of the set-ring. Fig. 35 6 is an internal side view of the other half of said section. Fig. 7 is a view in perspective of the halves of said section partly assembled showing the manner in which they are jointed or fastened together. Fig. 8 is a vertical 40 section thereof. Fig. 9 is a side view of a shaft with both sections of the set-ring thereon and partly screwed together. Fig. 10 is a similar view showing the set-ring sections completely screwed together and in final position on the shaft. Fig. 11 is a section on the line 11—11 of Fig. 10.

45 Referring specifically to the drawing, the set-ring or collar is in two sections indicated at 15 and 16, respectively. The section 15 has an opening 17 for the shaft 18, and on one side a projecting externally-tapering and threaded sleeve 19 through which the shaft also extends. The sleeve screws into a tapering and threaded bore 20 in the section 16.

Both sections are split or halved so that 55 they can be placed on the shaft without removing the latter from its bearings. The two halves of the section 15 are indicated at 21 and 22, respectively, and on one side thereof are grooves or channels 23, which when 60 the halves are placed together, form an annular groove or channel. The two halves of the section 16 are indicated at 24 and 25, respectively, and on one side thereof are shoulders 26, which when said halves are 65 placed together, form an annular shoulder. When the sections 15 and 16 are assembled on the shaft the shoulders 26 enter the grooves 23.

The sleeve 19 is rendered reflexible by 70 making longitudinal saw cuts or kerfs 27 therein so that when said sleeve is screwed into the bore 20 it will be forced against the shaft to tightly grip the same.

The parts 24 and 25 are fastened together 75 by a dovetail joint, they being provided at their meeting ends with dovetail tenons 28 and mortises 29, the tenon of one of the parts entering the mortise in the other part, whereby they will be securely fastened together on 80 the shaft.

To place the ring on the shaft, the parts 24 and 25 are placed on the shaft from opposite sides thereof and slid lengthwise thereon toward each other and interlocked by sliding 85 the tenons 28 into the mortises 29. The parts 21 and 22 are then placed together on the shaft from opposite sides thereof, and the sleeve 19 inserted into the bore 20 and screwed thereinto. As the sleeve is flexible 90 it will grip the shaft when the sections are screwed together whereby the ring will be securely fastened on the shaft. Each ring section has holes 30 for a spanner or other suitable tool for screwing the parts together. 95

When the ring is secured to the shaft as herein described, there are no screw-heads or other projections extending beyond the periphery of the ring. The ring may be made of any size to fit any sized shaft.

The object in breaking the joint by having the shoulders 26 engage with the grooves 23 is that in some cases the ring might be securely affixed to the shaft and screwed up as tightly as it would go, and yet the two sections of the ring might not come absolutely together. In such a case the joint herein described would prevent anything from get- 100 105

ting between the two sections of the ring and becoming entangled on the threads of the sleeve.

I claim:—

5. A set-ring for shafts comprising a split ring having on one side a projecting flexible externally-threaded sleeve, and an annular groove at the base of said projection; a split nut screwed on the sleeve, and having on one side an annular shoulder entering the afore-

said groove; there being means for fastening the nut-sections together.

In testimony whereof I have signed my name to this specification in the presence of two subscribing witnesses.

GEORGE H. BEST.
